UNITED STATES PATENT OFFICE.

JOHN BECKMAN, OF YOSEMITE VALLEY, CALIFORNIA.

GAGE.

1,148,430.

Specification of Letters Patent. Patented July 27, 1915.

Application filed September 29, 1914. Serial No. 864,188.

To all whom it may concern:

Be it known that I, JOHN BECKMAN, a citizen of the United States, residing at Yosemite Valley, in the county of Mariposa and State of California, have invented new and useful Improvements in Gages, of which the following is a specification.

The invention relates to gages, and more particularly to the class of shingle gages for 10 use on hatchets.

The primary object of the invention is the provision of a gage wherein it is made with a clamp so that it can be readily and easily mounted upon and fastened to the blade of 15 a hatchet for use in laying shingles so that the latter may be accurately placed and the hatchet used in the ordinary well known manner.

Another object of the invention is the provision of a gage wherein the same is of 20 novel form to permit the adjustment thereof when mounted on the blade of the ratchet for the setting of shingles.

A further object of the invention is the 25 provision of a gage which is simple in construction, reliable and efficient in use, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a side elevation of a hatchet known as a shingling hatchet, showing the gage constructed in accordance with the invention mounted thereon. Fig. 2 is a sectional view on the line 2—2 of Fig. 1. Fig. 3 is a perspective view 40 of the gage detached from the hatchet.

Similar reference characters indicate corresponding parts through the several views in the drawing.

Referring to the drawing in detail, A 45 designates a shingling hatchet, which is of the ordinary well-known construction, and is provided in its blade with an aperture 5 for the mounting of the shingling gage hereinafter fully described.

50 The shingling gage comprises a pair of clamping plates 6 connected together

through the medium of a hinge or pivot 7 so that the members can be swung together or opened. The inner meeting faces of the members near the pivoted end thereof are 55 formed with semi-circular channels or grooves 8 which are intersected by teeth 9, and these grooves or channels 8 are adapted to receive the stem 10 carrying a gage foot 11, the said stem being formed with 60 opposed transverse notches 12 diametrically opposite each other and in which engage the teeth 9 for the fastening of the stem when adjusted, and the clamping members 6 are fastened upon the blade of the 65 hatchet A in a manner presently described.

The inner faces of the members 6 are formed with cut away portions 13 to accommodate the thickness of the blade of the hatchet A, and loosely passed through one 70 of the said members 6 is a screw member 14 which is threaded in the other member 6 and is also passed through the aperture 5 in the blade of the hatchet A so that on the tightening of the screw 14 the members 6 75 will be firmly clamped upon the blade in the position as shown in Figs. 1 and 2 of the drawing, and also the stem will be fastened in adjusted position between the members 6 so that it will lie parallel with the longer 80 outer edge of the hatchet A to be positioned for use in laying shingles.

From the foregoing description, taken in connection with the accompanying drawing, it is thought that the construction and manner of use of the device will be clearly understood, and therefore a more extended explanation has been omitted.

What is claimed is:—

1. A gage comprising a pair of swingingly connected members having grooves in their inner faces, teeth presented in said grooves, a notched stem received by the grooves in the members and adapted to be locked by the engagement of the teeth in 90 the notches in said stem, a gage foot on the stem, and means for clamping the members upon the blade of a hatchet.

2. A gage comprising a pair of swingingly connected members having grooves in 100 their inner faces, teeth presented in said grooves, a notched stem received by the

grooves in the members and adapted to be locked by the engagement of the teeth in the notches in said stem, a gage foot on the stem, and a screw member mounted in the 5 members and engageable with the blade of a hatchet for the clamping of the same thereon.

In testimony whereof I, affix my signature in presence of two witnesses.

JOHN BECKMAN.
